UNITED STATES PATENT OFFICE

2,586,071

BOOK OF PERSPECTIVE VIEWS

Pedro Manen-Mayol, Barcelona, Spain

Application February 9, 1949, Serial No. 75,379
In Argentina August 20, 1948

1 Claim. (Cl. 40—65)

1

The present invention relates to a device in the form of a folding book so constructed that it may be used either for purposes of instruction or merely for amusement. The physical and psychological principles which are responsible for the results obtained by this invention include the reflection of light from distinct and separated planar surfaces, the superposition of images upon transparent bodies, the effects of different hues, shadows, etc. These are all easily displayed in a series of scenes interlaced to accord with reading matter, such as a tale or story, to which they lend a clear idea of the text. Likewise there is also afforded the possibility that the same viewer of this device can bring about changes in the prepared dioramas for certain effects, as well as also certain movements of the folding portions, all of which will contribute not only to the securing of an infinite number of scenes, but likewise will stimulate the ingenuity of the operator, by affording him the opportunity of determining the correct interleaving of the constituent parts of the device.

One object of the invention is to afford a dioramic book which is cheap and simple to construct, and which yields perspective or three-dimensional effects.

Another object is to afford a book of this type which shall be capable of interchange or substitution of certain elements thereof, whereby the skill of the operator is cultivated.

Further objects and advantages of this invention will become apparent from the following description and from the hereunto annexed drawings, which disclose a single possible embodiment of the instant invention, described solely by way of example and without thereby limiting the scope of the invention.

Referring now to the drawings:

Fig. 1 represents a book embodying the present invention, completely unfolded;

Fig. 2 represents the book of Fig. 1, but in a half-folded position;

Fig. 3 shows a detail of one of the dividing members of the book, and

Fig. 4 shows a partial detail of one of interchangeable dioramic elements thereof.

In all the figures, like reference numerals are appended to identical or similar elements, and the following description is to be read simultaneously upon a plurality of the figures of the drawings.

The dioramic book consists of two covers, 1 and 2, each of which is hinged for a portion approximately equal to half the width thereof, so that

5 at the points indicated by 3 and 4, these covers possess the requisite flexibility.

Upon the fixed portions 5 and 6 of the above described covers are arranged four or more sections of thick paper or other similar material, which easily are spread out as shown in the drawings, and constitute the dioramas:

10 The diorama located at the extreme front, 1, as well as the diorama located at the extreme rear, 8, are of a height substantially equal to that of the covers 1 and 2, whilst the intermediate dioramas 9, 9, are made to be narrower, since these latter are intended to be removable in order that they can be exchanged for other and different representations.

15 The distance comprised between both covers, namely the length of the dioramas, is sub-divided into distinct compartments. In the illustration there are shown four such compartments, but a greater or less number may be employed, if so desired.

20 For the purpose of providing a certain freedom of movement to both the fixed dioramas 1 and 8, as well as the removable dioramas 9, 9, in order to accomplish the folding of these elements, as shown in Fig. 2, there have been provided in the intermediate spacing elements 10, a series of symmetrically arranged apertures 11, each of which is provided with a convergent passageway 12, extending towards the exterior in such fashion that through each one can be inserted the corresponding diorama, by means of an opening 13, provided in these latter, as displayed in Fig. 4.

25 In this manner the fastening of the transversal spacers 10 is able to be perfectly assured, when the portions 14 of the dioramas are locked into the apertures 11. On the other hand, the transverse spacers will have arranged upon the lateral portions thereof interlocking with the dioramas, a series of prismatic projections 15, which latter are later lodged in the little apertures provided in the dioramas 1 and 8, thus fastening these last together with the removable dioramas 9, 9, and facilitating the rearward movement thereof, when folding the device as a whole, as shown in Fig. 2.

30 The dioramas 1 and 9 are provided, in each division thereof with an appropriate cut-out portion in accordance with the printed matter displayed upon the pages 16, which are found arranged directly behind the covers 1 and 2.

35 In this fashion, for example, the fixed diorama 1 would be provided with a cut-out 17, and the movable dioramas 9, would be provided with re-

spective cut-out portions, such as shown at 18 and 19.

Since the superposition of the cut-outs 17, 18 and 19 brings about a space, substantially free, between each one, thus producing an interesting scene, then the intensity of the light reflected from each surface of each diorama, the color of the same, the possibility of more or less shadow, and the semi-folded position of each diorama, all contribute to giving the spectator a more realistic view of the story which has been read on the pages 16.

While the dioramas have been, in the foregoing description, described as formed of fairly thick paper, which is usually relatively opaque, it is to be understood that it is possible to form the portions constituting the actual dioramas, or any individual portion, of a suitable material which shall be translucent or transparent, such as thinner and less opaque paper, suitable plastic material, and the like. When such materials are used, the partial or complete transmission of light will give rise to additional visual effects. For example, the reflection of colored light will alter the appearance of other portions of the diorama.

Other changes and variations of the embodiment herein described and shown will be apparent to those skilled in the art, and I am accordingly limited only by the scope of the hereunto appended claim.

What is claimed and desired to be secured by Letters Patent of the United States of America is:

A dioramic book comprising two spaced separate covers of relatively stiff material, a series of transversely foldable longitudinally disposed

dioramic sheets some of which are affixed to the covers, a plurality of transverse spacing elements intermediate the covers, interlocking means holding said spacing elements substantially rigidly joined to said dioramic sheets at the points where said sheets are foldable, said covers being provided with a flexible hinge-like portion substantially at the place where the front dioramic sheet is joined thereto, and said dioramic sheets being provided with registering apertures and display cut-outs, whereby when unfolded, said dioramic sheets are substantially rigidly held parallel to one another in separated planes.

PEDRO MANEN-MAYOL.
